OF D 17,730

DESIGN.

—o—
N. KOMORI.

CARPET.

No. 17,730.

Patented Sept. 20, 1887.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,730, dated September 20, 1887.

Application filed August 16, 1887. Serial No. 247,110. Term of patent 3½ years.

To all whom it may concern:

Be it known that I, NORIC KOMORI, of New York city, in the county and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 My design comprises a body part, A, and a border, B.

The body A consists of a grained or checkered ground-work, upon which are disposed in an irregular manner single flowers with leaves, or clusters of two or three small flowers with an occasional bud. The flowers are generally circular flowers, and are placed so as to present different sides to view. The whole design has an open appearance.

In the border B there is a narrow inner 25 margin. Next to this are grouped circular flowers and leaves similar to those appearing in the body portion A, but more closely grouped. Above this the design is of an open character, consisting of a grained or checkered 30 ground-work upon which single flowers or small clusters are scattered. The border is completed by an ornamental figure repeated to form an outer margin.

What I claim as new, and desire to secure 35 by Letters Patent, is—

1. In a design for carpets, the body A, substantially as shown.
2. In a design for carpets, the border B, substantially as shown.
3. The design for carpets, consisting of the body A and border B, substantially as shown.

NORIC KOMORI.
